UNITED STATES PATENT OFFICE.

RUSSELL J. HILL, OF GREELEY, COLORADO.

AUTOMATIC FLUID-CONTROLLING DEVICE.

Application filed August 11, 1927. Serial No. 212,339.

This invention relates to moisture controlling devices, and particularly to devices of this character in which the discharge of moisture may be controlled thermostatically or by hand.

The general object of the present invention is to provide an electro-magnetically operated valve which includes an electro-magnet energized or de-energized by the rise or fall of a mercury column or by the movement of some other thermostatically controlled device.

A further object is to provide a device of this character which may be adjusted so as to permit the almost constant discharge of steam or other fluid through a nozzle or cause a constant intermission in the discharge at short intervals.

A still further object is to provide a device of this character in which the valve may be used to control the passage of fluid through a multi-way conduit, operating to permit the passage through one conduit when the electro-magnet is energized and the valve moves to one seat and through the other conduit when the electro-magnet is de-energized and the valve shifts to another seat.

Other objects will appear in the course of the following description.

My invention is illustrated in the accompanying drawing, wherein:—

Figure 1 is a diagrammatic view partly in section of my fluid controlling device;

Figure 2 is a view showing the ends in elevation of different sized jet nozzles for the discharge pipe;

Figure 3 is a diagrammatic view showing the application of my control mechanism to one form of incubator;

Figure 4 is a like view to Figure 2 but showing the application of my fluid controlling means to another form of incubator;

Figure 5 is a side elevation partly broken away of a modified form of my controlling valve;

In the drawing, it will be seen that I have illustrated my invention diagrammatically, and referring to the drawing 10 designates a metallic pipe of any desired cross sectional area. This metallic pipe is formed in two sections 10 and 10^a, 10 being the inlet section which is joined by a coupling 11, this coupling being screw-threaded at its ends so as to engage corresponding screw-

threads on the ends of the sections 10 and 10^a. This coupling is sufficiently larger than the section so as to form a valve chamber 12 between the inner ends of the pipe sections and the inner ends of these pipe sections are formed to provide seats 13. Disposed within the casing constituted by the coupling 11 and the inner ends of the pipe sections 10 and 10^a is a metallic ball 14. The extremity of the pipe 10 is engaged by a plug or nozzle 15 having a central opening 16 through which a jet of steam is designed to be discharged by the pipe 10.

Surrounding the pipe section 10 is a coil 17 which, as will hereinafter be described, constitutes the coil of an electro-magnet, of which 10 is the core. Disposed in any convenient position is a thermometer or equivalent instrument 18. This is shown as a wet bulb thermometer, the extremity of which is surrounded by a tubular silk wick 19 which is reversible and has one end immersed in water.

Disposed in any desired position adjacent the lower end of the thermometer is a contact member 20 which engages with the mercury and which is connected by a wire 21 to any source of electric current, as the secondary coil 22 of a 110-volt transformer, the primary coil of this transformer being designated 23. A conductor 24 leads from this transformer to the coil 17. Disposed at any desired intervals upon the tube of the thermometer are the contacts 25. One of these contacts is shown as being disposed at the 60° graduation, another at the 85° graduation, another at 87° and another at 88°. This is purely illustrative and each one of these contacts 25 may be connected by a wire 26 to the wire 27, which leads from the coil 17.

It will be obvious now that when the mercury in the thermometer is at a relatively low point, that is below 60° in the arrangement of contacts illustrated in the drawing, no current will pass through the coils 17 as the circuit will be broken. When, however, the current rises to the 60° contact, assuming that this is connected to the wire 27 as, for instance, through the binding post 28, a circuit will be closed through the coil 17 and the electro-magnet formed by these coils 17 and the core 10 will be energized which will attract the ball 14 from the seat upon which it normally rests to the seat 13 so as

to close the pipe section 10 and prevent the passage of steam through the nozzle 15. As soon as the mercury has fallen, however, so as to break the circuit, the electro-magnet 5 will be de-energized and the ball 14 will fall by gravity away from the inner end of the pipe 10 and into the space between the two ends of the pipe 10, this space being defined by the periphery of the coupling 11. Any 10 one of the contacts 25 may be connected by the wire 26 to the binding post 28 and thus in the circuit which includes the electro-magnet and the secondary of the induction coil. The circuit which includes the secondary coil and the electro-magnet is preferably an 8-volt low tension circuit. The primary coil 23 will be connected preferably in a 110-volt circuit so that the voltage will be stepped down by this transformer from 15 110 volts to 8 volts. The nozzles or plugs 15 may be changed so that the hole 16 may be either $\frac{1}{16}$ " in diameter, $\frac{1}{8}$ " or $\frac{1}{4}$ " as desired, and obviously plugs with other diameters of openings may be used.

20 25 The silk wick 19 is kept wet by immersing one end in water in a small-necked glass bottle located near the wet bulb thermometer. Reversing the wick and filling the bottle with water are the only operations 30 involved. Steam under slight pressure will continue to pass through the valve into any given space until sufficient moisture accumulates in that space to reduce the evaporation on the wet bulb wick 19 and hence the rise 35 of the mercury in the column of the wet bulb thermometer. The base contact 20 and the one or more contacts 25 are located in such a way that at any given point or temperature the rise of the mercury column will 40 close the electric circuit, which in turn causes the electro-magnetic opening or closing of the ball check valve 14.

While in Figure 1, I show the ball check valve 14 as performing no function when 45 it is unseated except, of course, to permit the passage of steam or other fluid through the pipe sections 10 and 10^a, yet it will be understood that there may be a pipe extending from the coupling 11 or the equivalent 50 thereof which will be closed by the ball 14 when the ball falls by gravity on the de-energizing of the magnet. Thus a double action may be secured in the operation of this valve which will perform a very ad- 55 vantageous function in controlling heat in, for instance, "Buckeye" or like incubators where a retort or pressure cooker with a float check valve containing the water readily furnishes steam, as in the "Smith" mam- 60 moth incubator where a regular boiler furnishes steam. Such correlation of my elec- 65 tro-magnetic ball check valve with these two devices is shown in Figures 3 and 4, it being understood, however, that the mechanism to 70 which the ball check valve is applied is

shown diagrammatically and merely for the purpose of illustrating the application of the ball check valve to these situations.

Referring now to Figure 3, A designates the incubating chamber of a "Buckeye" incubator. This chamber has in it the thermostat *a*. The source of hot water is designated B and a pipe C leads from the source of hot water into the upper portion of the incubating chamber A. A return pipe D 70 leads from the lower portion of the incubating chamber A into the lower portion of the hot water tank or other source D and this return flow pipe is connected to the pipe C 75 by a pipe E. Disposed immediately above this pipe E is the ball check valve 14 which is adapted to close against the seat *e* formed at the upper end of the pipe E at its junction with the pipe C. Surrounding that portion of the pipe C in advance of the 80 branch E is the coil 17, the pipe *c* constituting the core of the electro-magnet and this pipe *c* at its junction with the pipe E being formed with a seat 13. The coil 17 may be connected to any suitable source of current or current may be induced therein by an induction coil or step-down transformer 85 90 95 22 and 23, as previously described.

The circuit through the wires 29 which connect the coil 17 to the source of current is broken at the single or double contact switch, illustrated diagrammatically in Figure 3 and designated 30. This switch is operated by the thermostat *a*, this thermostat being connected to one side of the circuit which includes the magnetic coil, and the switch blade 31 being adapted to be shifted to the contact 32 when the temperature rises. The ball valve 14 in Figure 3 is located in place of the valve used in the "Buckeye" heater 100 105 to check the intake of hot water to the radiator room and the energizing of the coil 17 acts to shift the valve 14 against the seat 13, thus cutting off the flow of hot water to the incubator but permitting the 110 flow of hot water from the pipe C into the branch pipe E and back to the heater by the return flow pipe D. On the de-energizing of the coil 17, the valve 14 returns to the 115 seat 13. It closes the by-pass to the boiler or heater B and permits the flow of hot water into the incubator or to the incubator coils of radiators and thus speeds up the flow of hot water to the radiator room. By controlling the energizing and de-energizing of 120 the coil 17 by means of a very sensitive electro-thermostatic switch such as is shown diagrammatically in Figure 3, a very great improvement and simplification of the controlling means for incubators of this character is secured.

In Figure 4 is shown the application of my invention to a "Smith" mammoth incubator. Here the pipe F leads from a boiler to the radiator coils G disposed within 125 130

the incubating chamber H. The pipe F terminates in a steam jet h, there being an automatic moisture controlling device just in advance of the steam jet. In this figure I have shown a shunt pipe I which connects to the pipe F outward of the incubating chamber H and discharges into this incubating chamber by two jets i and i'. An automatic moisture controlling device J may be disposed on the jet i. The pipe F at its junction with the pipe I is formed with the valve seat K and the pipe F is formed with a valve seat 13. A plug L is disposed above the valve seat K to permit the insertion of the ball valve 14.

It will be seen that on the exhaust or shunt steam pipe I there are two or more discharge jets and under these circumstances the valve 14 not only prevents overheating and temperature fluctuations but it eliminates the need of a cooling system by shunting the steam from the main radiator coils to an auxiliary steam discharge pipe entering the incubation chamber. This device arranged as stated will prevent late season climbing temperatures and still maintain the moisture conditions which are so necessary in order to permit the chicks to cup out clean. The control of temperature and moisture being thus secured, it is an easy matter to provide additional ventilation through application of external ventilation controls by the use of vent holes and dampers on top of the machine.

The ball check valve, it will be seen, is very simple in form, is extremely durable, may be positively acted on, and has great range of operation. This ball check valve with its electro-magnetic control is adapted to be used wherever a sensitive control of water, steam, gas, air or other fluid is sought. It may be adapted to scientific research or to many different industrial uses. It may be used to control flow of oil or gasoline in automatic filling stations or maintain humidity in bacteriological incubators, maintain proper humidity and spinning conditions in mills, be used for securing proper humidity in the home, and be used, as pointed out, in the artificial incubation of eggs. It is particularly desirable for use on all force draft types of incubators, as it permits of greater precision and unwavering electrical control of hot air, hot water, or steam heat without the expense of electric heat. It may be used to provide constant relative humidity at any desired percentage of temperature, which next to correct heat is the second basic factor in artificial incubation and thus makes possible more adequate ventilation without drying the embryos.

Under these circumstances, it is obvious that I do not wish to be limited to the exact features illustrated in the various drawings, that broadly my invention consists in the

use of a ball check valve operated by electro-magnetic force, and it will be seen that for many purposes the electric circuit for the control of the electro-magnet should be closed by the mercury in the wet bulb thermometer, although for many other industrial uses an aneroid type with a spring pointer and base and movable pointer contacts would suffice. It will be obvious, therefore, that I do not wish to be limited to the particular form of thermometer or thermostatic control which is illustrated. The steam can come from any generating source, either a regular boiler or from a special retort and, of course, my device is not limited for use with steam.

In Figure 5, I have illustrated a slight modification in details of construction, in which the pipe 10 which constitutes the core of the electro-magnet 17 carries the cap 15, as previously described, and as mounted upon this cap by the clamp 29 the swinging armature 30, the lower end of which is formed with a valve portion 31 closing the opening through the nozzle 15. This valve will swing away from the nozzle under the action of steam and may be made to swing away by gravity. The bracket 29 also carries an arm 32 having an adjusting screw 33 constituting a stop for the swinging armature 30 which will limit the outward movement of this armature. The screw, of course, is to be insulated or the bracket is to be non-magnetic. In the form shown in Figure 1, of course the ball 14 acts as the armature, whereas in Figure 5 the armature is pivoted, but the same principle of operation is used in both circumstances, the coils 17 being connected in precisely the same manner as the coils shown in Figure 1 to any source of electricity.

I do not wish to be limited to the use of a wet bulb thermometer, nor to the particular form of the contacts with which the mercury of the thermometer engages, nor to the particular means whereby the coil 17 is energized, as these may be varied without departing from the spirit of the invention, nor do I wish to be limited to the details of the arrangement shown as the drawing is purely diagrammatic and the arrangement may be varied through a wide range without departing from the spirit of the invention as defined in the claims. It will be seen that by connecting the upper contacts 82°, 85° and 88° to the coil 17 that a proper range of humidity can be secured for force draft incubators. Adjusting the contact at 60° (or any other desired temperature) permits of humidity control for the home or factory where a 68° room temperature is desired. Intermittent discharge of steam may be secured by enlarging the size of the jet opening and may be made almost continuous by reducing the size of the opening.

I claim:—

1. A fluid controlling structure comprising an approximately horizontal pipe, and a pipe leading therefrom at an angle thereto, there being an approximately vertical valve seat formed in the first named pipe and an approximately horizontal valve seat in the second named pipe at the junction of the two pipes, a ball valve normally resting against the second named seat and urged thereto by gravity, and electro-magnetic means associated with the first named pipe for causing the ball valve to shift from the second named seat to the first named seat upon the closing of an electromagnetic circuit, the breaking of the circuit through said electro-magnetic means permitting the ball valve to drop by gravity onto the second named seat.
  2. The combination with an incubator, a fluid heater and a pipe leading from the fluid heater into the interior of the incubator, a branch pipe extending from the first named pipe at an angle thereto, a valve casing disposed at the junction of the branch pipe with the first named pipe, the first named
- pipe having a seat disposed in said casing, and the branch pipe having a seat disposed in the casing, a metallic ball valve normally resting against the second named seat and urged thereto by gravity, and electromagnetic means including a coil surrounding the first named pipe outward of the seat therein, the coil when energized causing the ball valve to shift from the second named seat to the first named seat upon the closing of an electromagnetic circuit to the coil, thereby opening passage through the branch pipe and closing passage through the first named pipe, the breaking of the circuit through said coil permitting the ball valve to drop by gravity onto the second named seat to close the passage through one of said pipes and open passage to the first named pipe, the incubator having thermostatically controlled means for closing or opening said circuit.

In testimony whereof I hereunto affix my signature.

RUSSELL J. HILL.
